UNITED STATES PATENT OFFICE

164,502

COWBOY BOOT

John S. Justin, Jr., Fort Worth, Tex.

Application April 10, 1950, Serial No. 9,093

Term of patent 14 years

(Cl. D7—7)

To all whom it may concern:

Be it known that I, John S. Justin, Jr., a citizen of the United States and residing at Fort Worth, in the county of Tarrant and State of Texas, have invented a new, original, and ornamental Design for a Cowboy Boot, of which the following is a specification, reference being had to the accompanying drawing, forming part thereof.

Figure 1 is a perspective view of a cowboy boot showing my new design and illustrating a fabric covered top forming a part thereof and including a rough surfaced vamp.

Figure 2 is a side elevation of the cowboy boot illustrated in Figure 1.

The essential features of the invention are shown in solid lines. The vamp, counter and pull

straps are suede-like in appearance, and the leg has the appearance of substantially coarse textile fabric.

I claim:

The ornamental design for a cowboy boot, substantially as shown and described.

JOHN S. JUSTIN, JR.
